UNITED STATES PATENT OFFICE.

WALTER J. GADSBY, OF BOSTON, MASSACHUSETTS, ASSIGNOR TO ROXBURY CARPET COMPANY, OF SAME PLACE.

DESIGN FOR CARPET.

SPECIFICATION forming part of Design No. 11,681, dated March 16, 1880.

Application filed November 24, 1879. Term of patent 3½ years.

To all whom it may concern:

Be it known that I, WALTER J. GADSBY, of Boston, in the county of Suffolk and State of Massachusetts, have invented a new and original Design for Carpets, of which the following is a specification.

The nature of my design is fully shown in the accompanying photographic illustration.

The design has a dark ground broken by 10 rectangular light-ground centers A A A B B B, the centers A being of different color or tint from the centers B, and alternating with the latter longitudinally of the piece. C C C represent rectangular figures alternating with the 15 ground-centers A B diagonally of the piece.

The ground, the ground-centers A B, and the figures C are partly covered with superposed floral designs, foliage, and ferns, too intricate to admit of concise description.

I claim—

The design for a carpet, consisting of the dark ground, the rectangular ground-centers A B, alternating with each other longitudinally of the piece, the rectangular figures C, alternating with the centers A B diagonally 25 of the piece, and the superposed floral designs, foliage, and ferns, substantially as shown and described.

In testimony whereof I have signed my name to this specification, in the presence of two 30 subscribing witnesses, this 19th day of November, 1879.

WALTER J. GADSBY.

Witnesses:

C. F. BROWN,
J. E. TERRY.
